TELEVISION SYSTEM

Robert E. Shelby, Teaneck, N. J., assignor to Radio Corporation of America, a corporation of Delaware

Application September 29, 1942, Serial No. 460,042

3 Claims. (Cl. 178—7.2)

The present invention is directed to television systems and particularly to a form of television system wherein the effect of increased sensitivity of an electronic scanning tube may be attained.

In the prior art it has been known to use scanning tubes of the so-called "Iconoscope," "Image Iconoscope" or the "Orthicon" type, all of which have been described from time to time in literature. In such tubes there is included a mosaic electrode which consists of a conducting signal plate and a layer of dielectric material supported thereupon. Upon the dielectric material is an arrangement of photo-electric particles or globules which consists of a very substantial number of tiny particles of photo-electric material which are each mutually insulated one from the other. Accordingly, when the particles are subjected to the light of an image, photo-electrons are released and the change in status of the mosaic particle potential relative to the signal plate causes an electrostatic charge to be developed across the insulator where the magnitude of the individual charges is proportional to the brilliance of the optical image.

However, under many circumstances, with high detail of scanning, such as, for instance, the 525 line scanning presently used in television systems and the relatively high repetition rate of the order of 60 picture fields or 30 frames of double interlace picture per second, it is apparent that the time within which charges may be accumulated for release to an external circuit by the scanning action of a cathode ray beam scanning the mosaic is relatively short, and consequently the sensitivity of the scanning tubes is not as great as is often to be desired. If, however, provision is made for ways and means by which the time period between scanings may be lengthened out, then it is apparent that the effective sensitivity of any given elementary area of the mosaic would be increased, for it is substantially the effect that would be achieved by decreasing the field frequency without the resultant loss in the picture due to objectionable flicker, unless the picture reproducing device should have extremely long persistence.

Accordingly, the present invention comprises the system wherein it is an object to provide for increasing the effective sensitivity of scanning tubes of the cathode ray type.

Other objects of the invention are to provide a system wherein increased sensitivity may be obtained without unduly increasing the complexity of the system, nor yet the number

of its component parts, other than to increase the number of individual scanning tubes.

Other objects of the invention are those of overcoming one or more defects known in the prior art, whereby the loss of sensitivity, due to high repetition rates of scanning at the receiver, is not material at the transmitter.

Other objects and advantages of the invention will become apparent from a consideration 10 of the following specification in connection with the accompanying drawings, wherein the figures thereof schematically represent ways by which the invention may be practiced.

In the drawings, Fig. 1 represents one form of 15 system for using the invention, while in Fig. 2 a slight modification, using electronic switching, has been illustrated.

Referring now to the drawings, and first to Fig. 1 thereof, there has been shown two scanning tubes 11 and 12 which are each of the cathode ray type, and, for convenience of illustration only, those types of tubes known in the art as the "Iconoscope," which have been described at numerous places in the literature so 20 that further identification of a detailed nature is considered now to be unnecessary. It is, of course, to be understood that the "Iconoscope," being a well known form of scanning tube, has been shown in Fig. 1 merely as an exemplification of one form of suitable scanning tube, and, accordingly, any of the forms of scanning tubes hereinabove mentioned may be substituted. In many instances it is desirable to use the so-called "Orthicon" type of tube as a replacement 25 for the "Iconoscope" or the "Image Iconoscope." The "Orthicon" is shown particularly in conjunction with the system of Fig. 2, although it is to be understood that the system is to be in no way limited to any particular form of scanning tube. As an example of the use of the "Orthicon" tube, further reference to it has been made in the publications, for instance that entitled "The Orthicon, and television pick-up tube" by Rose and Iams, which appeared in the 30 "RCA Review", vol. IV, No. 2, on pages 186 to 199, for October, 1939, and also the same type of tube has been described in an article entitled "Television pick-up tubes using low velocity electron beam scanning", published by Rose and Iams in 35 the "Proceedings of the I. R. E.", vol. 27, No. 9, for September, 1939, including pages 547, et seq.

For purposes of illustration, the scanning tubes 11 and 12 comprise an evacuated envelope in which is included mosaic electrodes 13 and 14 55 which, as above stated, comprise signal plates

and photo-electric surfaces formed in a number of droplets, globules or particles of photo-electric material separated from the signal plate by a dielectric, such as mica, for instance. The light of an optical image, not shown, is adapted to be directed upon the mosaic elements 13 and 14 by way of suitable optical systems conventionally represented by the lenses 15 and 16 which are movable in the directions conventionally indicated by the arrows thereadjacent.

Where the object to be televised is not located at substantially an infinite distance from the camera or scanning tube, then it is, of course, apparent that by utilizing two physically separated scanning tubes 11 and 12 some objectionable introductions of parallax may result in the image, and for the purpose of correcting such distortion, systems of the general type shown by Burns Patents No. 1,931,890 and No. 1,968,476 may be relied upon for determining the position on the mosaic of the tube 12 where the impinging image is directed.

When the mosaics 13 and 14 are illuminated by the light of an image, photo-electrons are released therefrom which are collected by collecting electrodes, conventionally represented at 17 and 18, with the result that in the form of tube illustrated the photo-electric side of the mosaic, that is, the side facing the light image acquires a charge which is positive relative to the signal plate through suitable conductors 19 and 20 to suitable pre-amplifiers conventionally represented at 21 and 22.

In a neck of the scanning tubes 11 and 12 there is positioned an electron gun 23 and 24 which, under the application of suitable operating voltages supplied to the anode element thereof (not specifically shown) by way of the conductors 25 and 26, will apply a voltage gradient between the anode element and the cathode (not shown) which is preferably grounded at 27. Consequently, when the voltages are applied, electron beams 29 and 30 are developed within the tube and directed as a cathode ray beam to impact the photo-electric surface of the mosaic electrodes 13 and 14.

In order to cause the cathode ray beams 29 and 30 to traverse the bi-dimensional pattern of the mosaic elements, scanning yokes 31 and 32 are arranged to surround the neck portion of the cathode ray tube in order to deflect the developed cathode ray beams in a bi-directional pattern. For simplicity of illustration, the yokes are not shown as consisting of separate yokes for horizontal and vertical deflection, by which will be meant the rapid deflection and the relatively slow deflection, but it is well understood in the art that such arrangements may be used.

The scanning of the mosaic electrodes 13 and 14 by the cathode ray beams 29 and 30, as is well known, releases the charges accumulated by the mosaics to represent the picture or image focused thereupon, with the result that the signals representative of the image are transmitted via the conductors 19 and 20 to the pre-amplifiers 21 and 22 where the resultant signals are amplified to some extent.

The output energy from the pre-amplifiers is fed by way of the conductors 33 and 34 to emerge into a single conductor 35 which feeds its energy into a combining amplifier unit 36. This amplifier is of substantially conventional and well known form and comprises suitable thermionic amplifiers for amplifying the output signals from

the scanning tubes 11 and 12 to an extent desired for transmission to the suitable mixers, modulators and transmission channel in known manner by way of the conductor 37, for instance.

In order to provide for the deflection of the cathode ray beams within the scanning tubes 11 and 12, and at the same time to develop signals for synchronizing receiving apparatus with the transmitter scanning tubes by providing a train of synchronizing signals to accompany the image signals, a master oscillator 39, of known form, is provided. Generally speaking, this may consist of some suitable form of multi-vibrator or the like, and among the general forms of arrangements satisfactory for carrying out the purposes are those shown, for instance, in the book entitled "Principles of Television Engineering" by Donald G. Fink, published by McGraw-Hill Book Co., Inc., New York, 1940.

The master oscillator serves to control horizontal and vertical deflection control circuits, which are conventionally illustrated in block diagram at 41, and the output energy from this generator unit is then fed by way of the conductor 43 to energize the deflection coils 31 and 32. It is to be understood, in this connection, that the schematic representation of the drawings illustrates merely a single conductor and a single unit for applying the horizontal and vertical deflection energy to the coils, and again this illustration must be regarded as wholly and completely schematic and merely for the purpose of illustrating the general principles of operation since the deflection control unit and the like does not constitute a specific part of the invention.

Likewise, for blanking, the scanning beams 29 and 30 within the scanning tubes 11 and 12, during return motion, that is, during non-picture producing periods, there is provided a horizontal and vertical blanking signal generator unit 45 which is operated under the control of the master oscillator 39. The output energy from the horizontal and vertical blanking control unit 45 is then fed by way of the conductor 46 to supply energy to the control electrode (not shown) forming a part of the electron gun assembly (not shown) of the scanning tubes 11 and 12, so that during the return line or snapback period the scanning beams may be suppressed under the influence of a negative cutoff potential applied to the control electrode element. Simultaneously, the master oscillator 39 serves to control the production of line, field and frame synchronizing impulses, which are herein assumed, for purposes of illustration, to be developed within the unit 47, whose output is supplied by way of the conductor 48 to mix with that of the combining amplifier 36 in the conductor 37. In this way, and in accordance with standard practice, the synchronizing and control signals follow the image or field signals in ordinary sequence, as is standard practice in the art.

In order to provide anode voltage for both the pre-amplifiers 21 and 22 and the electron guns 23 and 24 of the scanning tubes 11 and 12, a source of anode voltage, conventionally represented at 49, is provided. This energy is then fed by way of a conductor 50 to energize the anode voltage supply line 25 for the gun of the scanning tube 11 and to energize the conductor 51 supplying anode voltage to the pre-amplifier 21. Likewise, voltage from the source 49 may be fed by way of a second conductor 52 to energize the anode voltage supply line 26 serving to supply the anode voltage of the gun 24 to the

scanning tube 12, and also to energize the supply line 53 for supplying anode voltage to the pre-amplifier 22.

So as to provide the connection of the source 49 to the conductors 50 and 52 alternately, the contact points 54 and 55 are adapted to alternately bear upon the armature 56 of a relay unit 57 which is energized under the control of an energizing coil 58. When the relay is de-energized by lack of any current flowing through the relay winding 58, the relay is biased by a spring 59, or the like, so as to press the armature 56 against the lower contact 55 and energize the electron gun 24 of the scanning tube 12 and the pre-amplifier. However, during time periods when the winding 58 is supplied with energy, the relay armature 56 is carried against the upper contact point 54 and energy from the source 49 is supplied to the anode of the electron gun 23 of the scanning tube 11, and also to the pre-amplifier 21 associated therewith.

In order to provide for alternately energizing and de-energizing the relay element 57, there is included a suitable prime mover 60 which is arranged to drive and rotate a commutating element 61 driven by way of the connecting shaft or link 62. The prime mover is preferably adapted to rotate at a rate coinciding with the frame frequency to be developed which, for a 2 to 1 interlace condition and with 60 fields of transmission per second, will amount to a rotational speed of 30 revolutions per second, or, where desired, the prime mover may be so geared as to rotate the commutator at this speed through either step-down or step-up gearing. In any event, to control the speed of the prime mover and to maintain it in synchronism with the cathode ray beams 29 and 30 within the scanning tubes, the connection is made by way of the conductor 63 to the output from the horizontal and vertical deflection control circuit unit 41, so that the same energy that is supplied to deflect the cathode ray beams in the transmitter scanner tubes may also serve to control the speed of rotation of the prime mover in order that exact synchronism be maintained with the rate of beam deflection.

The prime mover, in its rotation of the commutator 61, so provides that the source of voltage 49 may energize the relay winding 58 for a period corresponding to 180° of rotation of each turn of the commutator. This is provided by reason of the provision of the inner slip ring member 65 and the outer segmental commutator sections 67 and 68, of which it will be assumed that the latter section connects to the slip ring member by way of the connection 69 and is insulated from the section 67 by means of the insulator element 70. Thus, by virtue of the connection of the brush 71 to the outer commutating ring section 68, the conductor 69, the slip ring 65, the brush 72 and conductor 73 to ground 74, and, under such conditions, the scanning tube 11 will serve to supply energy to the pre-amplifier 21, whereas after the commutator rotates to the position, as shown, whereby the brush 71 bears against the commutator segment 67, it is apparent that there is an open circuit as far as passing energy through the armature or winding 58 is concerned, so that the relay armature 56 rests

against its lower contact 55, and the scanning tube 12 and pre-amplifier 22 are energized.

In this way it is apparent that alternate energization of two independent scanning tubes takes place and the time cycle of operation is such that the period permitted for charging of the mosaic elements, under the influence of the energizing light, is substantially increased, whereby the effective signal output, as supplied to the pre-amplifiers 21 and 22 is materially increased for any given light value. The result is that the objectionable noise is reduced substantially and the picture quality improved.

Now, making reference to the showing of Fig. 15, a modification of the system has been disclosed wherein the so-called "Orthicon" type of tubes 111 and 112 have been substituted for the "Iconoscope" tubes 11 and 12 of Fig. 1. The "Orthicon" tubes herein illustrated have been shown merely in diagrammatic form and include the mosaic structures 113 and 114 positioned at the end of the tube and upon which the light of the image is directed by means of the optical systems such as those shown at 15 and 16.

As in the arrangement of Fig. 1, the mosaic structures 113 and 114 of the "Orthicon" tube comprise, generally speaking, the signal plate, the insulating member and the light sensitive particles supported upon the insulator, as is well known. The light of the image projected through the optical systems 15 and 16 is projected upon the mosaic electrode of the "Orthicon" and electrostatic charges are built up which are scanned, but in this case, the scanning is by a low velocity electron beam, as explained in the publications cited.

For purposes of illustration, the focusing coils 115 and 116 have been shown as surrounding the complete length of the "Orthicon" tube and supplied with energy from a source 117. The deflecting coil for deflecting the electron beam within the tube in a vertical direction is represented schematically by the coils 119 and 120 surrounding the end of the "Orthicon" in the region between the deflecting plate pair 121 and 122 to which the horizontal deflection voltages are applied. The vertical deflecting coils are supplied with energy from the vertical deflecting control unit 44 which is to be understood as constituting a part of the vertical and horizontal deflection control unit shown in Fig. 1 as the unit 41. Similarly, the horizontal deflection control unit 42 constituting another part of the unit shown as 41 in Fig. 1 supplies its energy to the deflecting plate pairs 121 and 122, as indicated.

In order to develop the electron beam within the "Orthicon" tube for scanning the mosaic electrodes 113 and 114, provision is made for an electron gun element 123 and 124 which comprises the usual electron emitter accelerating anode and a suitable control anode. The accelerating anodes are supplied with energy from any suitable source of positive voltage, such as that represented schematically by the potential source 125 which feeds its energy by way of the conductors 127 and 128 to the anode member of the electron gun. The cathode member is suitably connected to ground in well known manner, as indicated. Likewise, for convenience of illustration, one end of the deflecting coils, the focusing coils and the deflecting plate pairs is shown as connected to ground.

To control and modulate the intensity of the electron beam developed within the electron gun 123, as for instance to provide for return line

blanking, there is provided the usual control or grid electrode formed as one element of the gun structure. The grid or control electrode of the gun 123 may be connected by way of a conductor 129 and 130 to an electron switch 131. Similarly, the control electrode or grid of the gun element 124 connects by way of the conductors 132 and 133 to the electronic switch 131. There is also a connection from the electronic switch 131, by way of the conductors 130 and 134, to a pre-amplifier unit 21, and by way of the conductors 133 and 135 to a second pre-amplifier unit 22. The pre-amplifier units 21 and 22 are connected with the signal plates of the mosaic electrodes 113 and 114 of the two separate "Orthicon" tubes 111 and 112 and serve in the same connection as did the pre-amplifiers 21 and 22 explained in connection with Fig. 1 to amplify the output signals from the scanning tubes. The output of the pre-amplifiers 21 and 22 is supplied by way of the output conductors 33 and 34 to the combining amplifier unit 36, all as explained in conjunction with the showing of Fig. 1.

The conductors 134 and 135 which feed energy from the electronic switch will be assumed herein to supply cut-off biasing voltages on the amplifiers 21 and 22 at predetermined points in the operational cycle of the device. Similarly, the conductors 129 and 132, which derive energy from the electronic switch 131, will also be assumed to provide negative or cut-off biasing voltages to the control or grid electrode of the electron guns 123 and 124 of the tubes 111 and 112.

If now, it be assumed that a suitable source of biasing voltage 139 is provided and arranged to feed its output energy into the electronic switch unit 131, it can be understood readily that if the electronic switch is adapted alternately to connect the source 139 with the pre-amplifier 21 and the control electrode of the gun 123 on the one hand, and the pre-amplifier 22 and the control electrode of the gun 124 on the other hand, that each of these units may, when energized by the bias voltage 139 through the electronic switch, be carried to a cut-off state.

The electronic switch herein is shown merely in diagrammatic form although it is to be understood that such switches are well known in the art and have been described, for instance, in the patents granted to Roys et al., No. 2,089,430, granted August 10, 1937, and to Shumard, No. 2,146,862, granted February 14, 1939.

As was explained in the aforesaid patents, the electronic switch units, such as that now conventionally represented as 131, are adapted to be triggered by some suitable source of energy which, in the arrangement of Fig. 2, is connected to the electronic switch by way of the conductor 141, and since it is desired, from what has been above stated, to provide a system wherein the tubes 111 and 112 are alternately functioning, it is apparent that the electronic switch unit 131 can readily be controlled from the vertical deflection control unit 44, which is done by way of the connection established through the conductor 141 between the vertical deflection control unit 44 and the electronic switch 131. Accordingly, the electronic switch 131 serves, following the receipt of one signal showing the completion of one vertical traversal of the mosaic electrodes of the scanning tubes, to switch the bias voltage source to one pre-amplifier and its associated electron gun to render it inoperative to produce signal output, and then immediately when the tube which has been previously rendered inoper-

ative is to be carried to an operative state, the bias is removed from the associated pre-amplifier and electron gun and applied to the pre-amplifier and electron gun of the tube which is 5 to be rendered in a negative state, so that by alternately switching the control from one "Orthicon" to another, it is apparent that the same effects secured by the switching unit 61, as driven from the unit 61, are achieved in a purely electronic manner by the apparatus conventionally illustrated in Fig. 2.

Similarly, in the arrangement of Fig. 1, horizontal and vertical blanking is applied to the "Orthicon" units 111 and 112 by way of the 15 conductor 143, shown as supplying energy from the horizontal and vertical blanking unit 45 into the control electrode element of the electron gun of each of the "Orthicon" tubes. In order to prevent any possibility of reaction between the 20 electron switch 131 and the horizontal and vertical blanking unit 45, it is frequently desirable to include a buffer amplifier (not shown) in the lead 143 between the horizontal and vertical blanking unit and the electron guns of the tubes, 25 all as is customarily practiced in the art.

For the purpose of supplying the line, field and frame sync signal output to be combined with the output of the preamplifiers 21 and 22 as such outputs are fed by way of the conductors 33 and 30 34 to the combining amplifier 36, provision is made by way of the conductor 48 for mixing this line, 35 field and frame sync signal output in the output of the combining amplifier 36 in the conductor 31. This combined signal output is then fed to the usual mixers, modulators and transmission channels in well known manner.

In order to supply the biasing cut-off voltages to the pre-amplifier units 21 and 22, such units 40 may frequently consist of one or more tubes of the tetrode type, so that the signal output from the mixer elements of the "Orthicon" tubes may be fed to the #1 control grid of the amplifier tube in the preamplifier unit and the biasing of the cut-off voltage to be fed to the #2 grid of such tubes, and under conditions which the #2 45 grid is maintained at a negative state, it is apparent that no output voltage will be derived from the pre-amplifier units. In this way it is apparent that provision is made for controlling the control grid voltage in the electron gun and pre-amplifiers, rather than by way of a control of the high voltage supply of the pre-amplifier and electron gun as shown in Fig. 2.

It is understood, however, that both systems 55 are generally equivalent and have been illustrated to show the wide variance in selection of circuit arrangements. It is to be understood further that any and all types of electronic switch elements may be utilized, and that for the purpose of these considerations the electronic switch and the mechanical switch are deemed to be the equivalent of one another, as are the various types of scanning tubes illustrated.

Furthermore, it is to be understood that the 60 arrangements herein shown have all been schematically represented and therefore the particular illustrations do not necessarily depict the exact arrangement utilized in practice.

Having described my invention, what I claim 70 is:

1. In a television scanning system, a pair of image scanning tubes each adapted to receive a substantially like light image, each of said image scanning tubes having a mosaic electrode upon which electrostatic charges representative of the

impressed images are adapted to be accumulated upon the projection of an image thereon, means included in each of the scanning tubes for developing an electron beam, a source of beam deflection energy for deflecting the developed electron beams to cause said beams to scan the mosaic electrodes to produce signal energy output, a pre-amplifier connected with each of the mosaic electrode elements of the tubes to receive the output energy therefrom for amplification, a combining amplifier to receive the output energy from the separate pre-amplifiers, and switching means for alternately rendering the independent scanning tubes and the associated pre-amplifiers operative and inoperative.

2. In a television scanning system, a pair of image scanning tubes each adapted to receive a substantially like light image, each of said image scanning tubes having a mosaic electrode upon which electrostatic charges representative of the impressed images are adapted to be accumulated upon the projection of an image thereon, means included in each of the scanning tubes for developing an electron beam, a source of beam deflection energy for deflecting the developed electron beams to cause said beams to scan the mosaic electrodes to produce signal energy output, a pre-amplifier connected with each of the mosaic electrode elements of the tubes to receive the output energy therefrom for amplification, a combining amplifier to receive the combined output energy from the separate pre-amplifiers, and switching means synchronized by said beam de-

flection energy source for alternately rendering the independent scanning tubes operative and inoperative and simultaneously render the associated pre-amplifier operative and inoperative.

- 5 3. In a television scanning system, a pair of image scanning tubes each adapted to receive a substantially like light image, each of said image scanning tubes having a mosaic electrode upon which electrostatic charges representative of the impressed images are adapted to be accumulated upon the projection of an optical image thereon, means included in each of the scanning tubes for developing an electron beam, a source of beam deflection energy for deflecting the developed electron beams to cause said beams to scan the mosaic electrodes to produce signal energy output, a pre-amplifier connected with each of the mosaic electrode elements of the tubes to receive the output energy therefrom for amplification, a combining amplifier to receive the output energy from each of the separate pre-amplifiers, a source of bias voltage adapted when applied to render the scanning tubes inoperative to produce a scanning beam and the pre-amplifiers inoperative to amplify signal energy output, and switching means for alternately applying the biasing voltages to the individual scanning tubes and associated pre-amplifiers so that signal energy output representative of the impressed light image appears in the combining amplifier alternately from each of the independent scanning tubes.
